IGNITION CIRCUIT AND OTHER LOCK

Filed Nov. 12, 1930

UNITED STATES PATENT OFFICE

VICTOR L. GILPIN, OF BALTIMORE, MARYLAND

IGNITION CIRCUIT AND OTHER LOCK

Application filed November 12, 1930. Serial No. 495,240.

This invention relates to improvements in locks and it consists of the constructions, combinations and arrangements herein described and claimed.

An object of the invention is to provide a lock for an ignition or other electrical circuit, embodying a switch by which the circuit terminals can either be bridged or released by the operation of a combination mechanism or a key cylinder by which the contactor of the switch is carried, said key cylinder being an indispensable part of the combination mechanism in that the tumblers of said cylinder are relied upon first as the connecting element with the combination mechanism when the latter is used, and second as the means by which disconnection with said mechanism is established when the key cylinder alone is desired to be used.

Another object of the invention is to so combine the lock switch in the instrument board of a motor vehicle that said instrument board shall function as a part of the lock.

A further object of the invention is to provide a lock in which the reduction of the working parts to a few in number and to the utmost simplicity and arrangement do not detract from the efficiency of the lock in the least.

Other objects and advantages will appear in the following specification, reference being had to the accompanying drawings in which,

Figure 1 is a perspective view of a portion of an instrument board showing parts of the improved lock combined therewith.

Figure 2 is a vertical section taken on the line 2—2 of Figure 1, the portions behind the instrument board being shown.

Figure 3 is a cross section taken on the line 3—3 of Figure 2, illustrating the initial engagement of the tumbler pin with the tumbler disc projection at the beginning of working the combination by turning the knob to the right.

Figure 4 is a similar view illustrating how the dog drops into the alined notches upon a reversal of the knob.

Figure 5 is a similar view illustrating the abutment as having caught up with the dog

upon the continued turning of the knob to the left, the final circuit closing position being denoted by the dotted line position of the dog.

Figure 6 is a cross section taken on the line 6—6 of Figure 2, particularly showing the tumbler pin connection with the knob-carried actuator disc.

Figure 7 is a section taken on the line 7—7 of Figure 2.

Figure 8 is a sectional view similar to Figure 2 illustrating the use of a key to actuate the contactor independently of the combination mechanism.

The herein disclosed lock is of general application, and its use as a means for controlling an electrical circuit is merely described for the purpose of illustration. To the latter end it is an improvement on the automobile and other lock disclosed in an application of Victor L. Gilpin, filed February 18, 1929, Serial No. 340,963.

That lock has provisions for simultaneously locking a steering post and opening an ignition circuit and vice versa, while the instant lock is confined solely to the control of a circuit which can be regarded as an ignition circuit. This lock is so reduced and simple in its parts that it is contemplated to make it economical to throw the lock away should the occasion for an internal repair arise and substitute it by another.

This statement is not to be construed as a lack of merit in the lock or as the possibility of anything going wrong because the contrary is the case in both instances. But the point is that the metallic stampings or castings are so few and simple that the lock can be marketed at a low cost, enabling the owner to readily replace it just as he would an inexpensive watch.

Reference is made to the drawings. The core of the lock comprises a key cylinder or barrel 1 (Fig. 2) which contains a plurality of tumblers 2 which tumblers are under individual spring pressure so that they normally project out of an open side of the barrel into either one of a pair of longitudinal slots 3 (Fig. 2) of a sleeve 4 immediately surrounding the barrel. The cylinder lock 1 is of a

known type, and its details, other than the tumblers 2, are omitted, it being sufficient to understand that the tumblers are always under spring pressure so that they will occupy 5 one of the slots 3 when not retracted by a key (Fig. 8).

For the purpose of the latter the cylinder 1 has a key way 6 (Fig. 8), and when the key 5 is inserted its wards 7 produce a simultaneous retraction of the set of tumblers 2 out of the slot 3 (Fig. 8) and into the cylinder 1, leaving the surface of the latter perfectly flush and capable of being turned with utmost freedom by means of the key 5 without disturbing the combination mechanism which surrounds the cylinder or core 1.

From this it will be understood that in the absence of the key 5 the tumblers 2 will be extended into one of the slots 3. The tumblers thus secure the cylinder 1 to the sleeve 4 so that these parts virtually comprise a unit. The inner reduced end 8 (Fig. 2) of the cylinder 1 carries a disc 9 of insulation to which a metallic contactor 10 (Fig. 7) is secured in any ordinary way, for example by means of a pair of rivets filed flush. This contactor is engageable with the terminals 11 of an electrical circuit 12 which may be an ignition switch or any other circuit which it is desired to close. By inserting the key 5 (Fig. 8) and turning the cylinder 1 as already pointed out the circuit 12 can be closed without regard to the combination mechanism. A screw 13 secures the disc 9 to the end 8. A flat plate 14 (Fig. 9) prevents turning of the disc relatively to the end 8.

The inner end of the sleeve 4 terminates in a stop disc 15. The cylinder 1 obviously turns in reference to this disc as it always does in reference to the sleeve 4 when actuated by the key 5. A dog 16 is pivotally connected to this disc at 17 (Fig. 3). The head 18 is made broad enough so that its nose 19 will span a tumbler disc 20 and ring 21 (Fig. 2) and ride on the rims of these two members.

The disc 15 can be turned to the left or right, and the turning is limited by the engagement of a lug 22 (Fig. 3) with the ends of an arcuate slot 23 in the disc. The lug 22 is struck in or otherwise arranged on a casing 24 (Fig. 2) in which the disc 15 fits with other members of the combination mechanism. A slightly raised dome 25 makes room for the outer part of the dog head 18 when the combination is "off" and the switch is locked. Otherwise the outer part of the head rides against the casing 24 when the combination is "on" as in the movement leading up to unlocking.

Hubs 26, 27 and 28, respectively of the disc 20, ring 21 and of an actuator disc 29 have bearing on the sleeve 4. A washer 30 seated tightly on the sleeve 4 retains the hubs 26, 27 in the space adjacent to the stop disc 15. These hubs are independently and freely re-

movable in the space. The washer 30 fits in a circular groove 31 (Fig. 2) in the disc 29 thus bringing the adjacent confronting faces of the disc 29 and ring 21 close together.

A tumbler pin 32 (Fig. 3), fixed crosswise of the ring 21 (Fig. 2) like the head of a T always engages at one end in a radial slot 33 (Fig. 2) that branches from the groove 31 (Fig. 6), and at the other end is engageable with a projection 34 (Fig. 3) on the near side of the tumbler disc 20. The hub 28 extends forwardly where it terminates in a knurled knob 35 (Fig. 1). The end of the key cylinder 1 and the key way 6 appear at the face of the knob.

The knob 35 projects through a hole 36 in the instrument board 37, in which hole the knob is turned first to the right, then to the left in order to work the instant combination. A circular dial 38 is permanently secured to the hub 28 (Fig. 2) immediately behind the instrument board 37 so that its numerals 39 and graduations 40 can easily be seen at an opening 41 in the instrument board. The numerals and graduations are read in reference to a pointer 42 that extends up from one edge of the opening.

It is to the foregoing extent that the lock and instrument board are combined, the latter functioning as a part of the lock inasmuch as the pointer 42 constitutes the place in reference to which the manipulation of the combination mechanism is begun. The combination herein adopted is "26" to the right, that is to say a turn of the knob 35 to the right until graduation 43 (Fig. 1) registers with the pointer 42, then a turn to the left until the dog 16 catches in the manner presently explained. The instrument board 37 is desirably embellished with ornamentation 44 around the opening 41. This may either comprise an attached plate or an embossed or engraved design.

The casing 24 has a closure cap 45 (Fig. 2) on its forward end. When the assemblage of the parts is made the casing is permanently secured in the cap so that it cannot be pulled off. A plate 46 (Figs. 2 and 7) fits the casing 24 immediately behind the stop disc 15 and is held from turning by the fitting of this notch 47 (Fig. 2) over the same lug 22 that limits the turning of the stop disc 15.

This plate 46 acts as a stop plate for the key cylinder 1. The key cylinder has a pin 48 (Fig. 7) that projects into an arcuate passage 49 that communicates with the hole 50 in the center of the plate receiving the inner reduced end 8. Upon inserting the key 5 and turning the key cylinder 1 in order to supersede the combination mechanism in the manner previously indicated, the motion to the right or left will be limited by the engagement of the pin 48 with the ends of the passage 49.

Swagings 51 in the casing 24 (Figs. 2 and 7) keep the plate 46, and the parts in front

of it, in place. A cover 52, fitted over the swaged rim of the casing protects the contactor 10 and the circuit terminals 11. These are suitably mounted on insulation 53 (Fig. 7) inside of the casing. A bracket 54 (Fig. 7), fixed behind the instrument board, receives the casing 24, and when its coacting yoke 55 is screwed or otherwise secured in place at 56 (Fig. 7), the casing will be rigidly clamped in position.

Reference is again made to the tumbler disc 20 and ring 21. The tumbler disc has a notch 57 (Fig. 3) which is brought into position beneath the head 18 by turning the knob 35 (Fig. 1) to the right until the graduation 43 registers with the pointer 42. This bringing into position is accomplished by the pushing action of the tumbler pin 32 (Fig. 3) against the projection 34, the tumbler pin being on the ring 21 and the projection on the disc 20, it being remembered that the knob 35 has permanent connection with the ring 21 at 32, 33 (Fig. 2).

The ring 21 has a cavity 58 (Fig. 3) that extends in depth to the hub 27. The ends of the cavity are bounded by a wall 59 and an abutment 60. It is necessary to turn the knob 35 only a short distance to the left from the place of registration of the graduation 43 with the pointer 42 when the wall 59 will pass by the nose 19 (Fig. 4) and the head 18 will drop into the recess then composed of the registering notch 57 and cavity 58.

A continued turn to the left brings the abutment 60 against the nose 19 (Fig. 5) thus connecting the formerly free stop disc 15 with the knob 35 by means of the dog 16 so that the concluding turn to the left and to the extent of the slot 23 (Figs. 3 and 4) can be carried out until the dotted line position in Figure 5 is assumed. This concluding turn moves the contactor 10 into a bridging position across the terminals 11.

The operation is readily understood. Ordinarily the knob 35 can be turned either to the right or left with the utmost freedom, and when it is turned the numerals 39 and graduations 40 (Fig. 1) pass in review behind the pointer 42. The lock cylinder 1 remains stationary, and the hubs 27, 28, respectively of the ring 21 and disc 29, turn on the sleeve 4 as a bearing. The ring 21 and disc 29 turn as a unit because of the connection of the forward end of the tumbler pin 32 (Fig. 2) with the radial slot 33 of the actuator disc 29.

Assume the lock to be operated by means of the combination mechanism in order to close the circuit 12. The object will be to turn the contactor 10 (Fig. 7) into the bridging position across the terminals 11. Turn the knob 35 to the right until the graduation 43 registers with the pointer 42 (Fig. 1). This turn to the right (arrow *a*, Fig. 3) causes a push of the tumbler pin 32 against the projection 34 and a corresponding turn of the

tumbler disc 20 (arrow *b*, Fig. 3) until the notch 57 (Fig. 3) in the tumbler disc 20 comes into position beneath the nose 19 (Fig. 4).

Now turn the knob 35 to the left. The tumbler pin 32 departs from the projection 34 (arrow *c*, Fig. 4) leaving the tumbler disc 20 standing. The wall 59 will presently pass by the head 18 whereupon the nose 19 drops into the recess then formed by the registering notch 57 and cavity 58, the latter being in the ring 21.

A further turn to the left (Fig. 5) brings the abutment 60 against the nose 19. This now makes a connection of the knob 35, disc 29 and ring 21 with the stop disc 15 by means of the dog 16, and since the stop disc 15 is connected with the key cylinder 1 by means of the set of tumblers 2 it follows that the continued turning of the knob 35 to the left will impart the necessary motion to the disc 9 in order to carry the contactor 10 to the ultimate bridging position across the terminals 11.

Upon concluding the turn of the knob 35 to the left (arrow *d*, Fig. 5) the turning motion is imparted to the disc 15, shifting it to the dotted line position in Figure 5. The motion is limited by the slot 23 and lug 22, but during this motion the contactor 10 is carried to the bridging position across the terminals 11 to close the circuit 12 as already pointed out.

In order to again open the circuit the knob 35 is turned to the right. The wall 59 upon engaging the head 18 will push on the head and consequently on the dog 16, rotating the disc 15 until the right end of the slot 23 again engages the lug 22 (Fig. 5), whereupon a continued turn of the knob will cause the wall 59 to rise under the rounded nose 19 and lift the head 18 out of the erstwhile recess 57, 58.

The tumbler pin 32 has but a short additional distance to travel, still turning the knob 35 to the right when it will engage the projection 34 and move the notch 57 from under the head 18 thus totally destroying the combination. It might appear that the wall 59 would be stopped by the head 18 and the latter prevented from being ridden up and out of the foregoing recess. However, the wall is made on a slight incline, and in practice the head 18 is displaced with utmost ease.

Assume next that the combination mechanism is to be disregarded and the key 5 used instead. The key is inserted in the key way 6 of the cylinder 1 (Fig. 8) whereupon the wards 7 depress the tumbler set 2 and retract it from its former position in one of the slots 3. Since these tumbler pins formerly were the connection between the key cylinder 1 and sleeve 4, locking these two parts together, it follows that the retraction of the tumbler set leaves the cylinder 1 perfectly free for

independent turning. The key 5 is now turned to the left, the same as the concluding turning of the knob 35, the turn of the key 5 being limited by the pin 48 and arcuate passage 49 (Fig. 7). The contactor 10 is brought to the bridging position across the terminals 11 in the same manner as before and the circuit 12 is closed. A turn of the key to the right again opens the circuit and the removal of the key permits the tumbler set 2 to spring back into the slot 3 (Fig. 2).

While the construction and arrangement of the improved ignition circuit and other lock is that of a generally preferred form, obviously modifications and changes may be made without departing from the spirit of the invention or the scope of the claims.

I claim:—

1. A lock switch comprising a contactor, circuit terminals, carrying means by which said contactor is supported, combination mechanism for moving the carrying means thus to shift the contactor into terminal engaging and disengaging positions, means establishing a connection between said mechanism and carrying means thus to enable the movement, and means for displacing the connecting means from said mechanism and enable independent movement of said carrying means.

2. A lock comprising a switch, switch contactor carrier means, means to act on the carrier means to close and open the switch, means providing a connecting element between the operating means and the carrier means enabling said action, and means to disconnect said element from the operating means enabling independent action of the carrier means for closing and opening the switch.

40 3. A lock comprising a switch, a key cylinder directly carrying the switch contactor and being operable by a key to close and open the switch, a combination mechanism mounted on the lock cylinder also being operable to close and open the switch, and a set of tumblers providing a connecting element between the cylinder and combination mechanism for operation by the latter, said tumblers being displaced by the key to disconnect the combination mechanism.

45 4. A lock comprising a switch, a key cylinder directly carrying the switch contactor and being operable by a key to close and open the switch, a combination mechanism also being operable to close and open the switch, said mechanism including a sleeve with an opening, and a set of tumblers being part of the key cylinder, occupying the opening to enable operation of the cylinder by the combination mechanism, but being retractible from the opening by said key to release the combination mechanism and confine operation to the key cylinder.

65 5. A lock comprising a switch contactor, a combination mechanism arranged to be

worked to an established combination and thereupon to move the contactor, and a key cylinder directly carrying the contactor and including a standard tumbler set establishing normal connection with the combination mechanism but being disconnectible therefrom by the insertion of a key in the key cylinder for movement of the cylinder and contactor independently of said mechanism.

6. A lock comprising a combination mechanism including a sleeve with an opening, a key cylinder fitted in the sleeve and having a tumbler set normally occupying the opening to establish a connection, and a switch contactor carried by the cylinder being operable by the key cylinder either by the combination mechanism through said tumbler set or independently of the combination mechanism by the insertion of a key for the retraction of the tumbler set from said opening.

7. The combination of a switch contactor and an instrument board, a combination mechanism having a knob accessible at the instrument board for working said mechanism to a prearranged combination at which the contactor becomes movable by said mechanism, a calibrated dial movable with the knob, and a fixed pointer on the instrument board in reference to which the calibrations are read thus to indicate the extent of knob movements in said working of the combination.

8. A switch having a movable contactor, separate, optionally operative means by one of which the contactor is carried, and a displaceable connection between said separate means enabling movement of the contactor either by one of said means or compelling operation of both to produce said contactor movement.
